UNITED STATES PATENT OFFICE

FRED W. NEELY, OF CHICAGO, ILLINOIS

STATIONERY CABINET

Application filed September 9, 1929. Serial No. 391,436.

My invention relates to articles used accessory to typewriters for the aid of the typist, and more particularly to devices dealing with the supply of the paper sheets entering into the use of the typewriter, and my main object is to provide an article of this kind in the nature of a cabinet adapted to supply the paper sheets in the most handy position for insertion into the machine.

10 A further object of the invention is to provide the novel cabinet with means to support the paper sheets in a position most nearly to the angle naturally imparted to the sheets for insertion behind the typewriter platen.

15 A still further object of the invention is to locate the novel supply cabinet in a position directly behind the typewriter, whereby to place the cabinet contents within easy reach of the typist.

20 Another object of the invention is to build the novel cabinet with a series of shelves to receive in succession batches of the first sheets, the carbon sheets and the second sheets, whereby to dispose them in close yet separated order.

25 A significant object of the invention is to provide the novel cabinet with an extension tray which gives more immediate access to the sheets when manifolding.

30 A final but nevertheless important object of the invention is to design the novel cabinet along lines of extreme simplicity and compactness, whereby to render the article easy to handle and attend and inexpensive to produce.

35 With the above objects in view, and any others which may suggest themselves from the description and claims to follow, a better understanding of the invention may be gained by reference to the accompanying drawing, in which—

40 Figure 1 is a longitudinal section of the novel cabinet in connection with a typewriter desk, the latter being fragmentally shown and partly in section;

45 Figure 2 is a section on the line 2—2 of Figure 1; and

Figure 3 is a detail section taken on the line 3—3 of Figure 1.

50 In the routine of the average stenographer

or typist, the grouping or assembling of the paper sheets preparatory to their insertion into the typewriter is a task which requires considerable attention, care and time. Usually, the first sheets are found in one of the desk drawers, the second sheets in another drawer, and carbon sheets in a place perhaps more accessible, such as the top of the desk or a tray or basket. It will be evident that, to properly group a set of sheets, miscellaneous movements must be undergone by the operator to collect and assemble the sheets; and further movements must be undergone to jog them into alignment and to transport them in a body to the entrance into the typewriter in back of the platen. It will be appreciated that this work, repeated each time a set of papers is inserted into the typewriter, consumes a considerable portion of the operator's working day, not to speak of the nervous strain incident to the assembling task when the sheets are not readily found where expected or when they group or jog into line with difficulty. It has been my intention to relieve the operator of the details in connection with the grouping of the sheets whereby to avoid the difficulties outlined above and accomplish the foregoing objects to their fullest extent.

Referring specifically to the drawing, 5. 80 denotes the novel cabinet, the same being in the nature of a light sheet metal box with the front and rear open and the top 6 sloping toward the front. Inside the cabinet is an array of vertically spaced shelves 7, these 85 being approximately similar in angle to the top and fitting in wall grooves 8 to a point near their front ends where they are of reduced width to fit between the walls, as clearly shown in Figure 2. At this site, the shelves are made with a short horizontal portion 7a and a final upward bend or lip 7b; also midway between its sides each shelf is segmentally cut out in the corner between the section 7a and the bend 7b, as indicated at 7c. 90

95 The novel cabinet is designed to rest upon the back portion 9 of the typewriter desk 10, this position being a short distance to the rear of the typewriter 11; it may be of advantage, however, to insert between the cabi- 100

net and the top of the desk a special base or platform 12 with slideways 12a along which the cabinet may be moved toward or from the typewriter to suit the reach of the operator. However, it is essential that the bottom of the cabinet proper be slightly above the entrance guide 13 of the typewriter.

In equipping the novel cabinet with a supply of paper sheets, I place the first 10 sheets, such as letter-heads or originals in inverted position and in a sizable batch upon the lowermost shelf 7 of the cabinet; next I place a similar batch of carbon sheets, sensitive face up, upon the second shelf; next I 15 place a batch of copy sheets upon the third shelf; and further, I alternate upon succeeding shelves with batches of carbon sheets and copy or second sheets. I have only shown a few shelves, these being sufficient for ordinary 20 purposes.

In the use of the device, the operator picks the topmost first sheet with the thumb and forefinger of the right hand by way of the shelf recess 7a and withdraws the sheet until 25 it may be gripped by the thumb and forefinger of the left hand; then the same process deposits a carbon sheet into the left hand; and finally the repetition of the process secures a copy sheet in the left hand together 30 with the previously withdrawn sheets. This assembly makes a set of one original, a carbon, and a copy; however, if more copies are required back of the original, the collecting process is repeated from the same two carbon 35 and copy shelves until the proper number of units is assembled into the set. Thus, the reach of the right hand to collect for more copy units than one is no longer or farther than in the single unit case. Both hands 40 may now withdraw the assembly of units and bring the same forward and down over the typewriter guide 13, to enter the typewriter back of the platen. It is thus seen that once the batches of sheets are inserted into the cabinet—preferably from the rear—in the 45 proper order and facing direction, the operator is relieved at the time the supply is needed of any concern as to the manner of assembling the sheets; also, the sheets are all in a position just behind the typewriter and in 50 line with each other for natural assembly. Further, the inclined position of the sheet batches makes it easy for the sheets to issue as withdrawn and to assume the downward 55 course necessary for entering into the typewriter.

The function of the frontal bend or lip 7b is obviously to serve as an end guard or stop for the batch of sheets; and the horizontal portion 7a of the shelf has for its object to induce the forward shift of the sheet batch from the top, as clearly shown in one of these shelf illustrations, so that it will be easier to pick off the top sheet of each batch with the forefinger, since such sheet will be in the foremost position.

In the case of manifolding, that is, where a relatively large number of copy units are required, I provide a special tray 14 in the bottom of the cabinet. This tray is extensible forwardly to a position over the typewriter, as indicated by dotted lines in Figure 1, and is designed to furnish a rest for each unit as it is withdrawn from the cabinet. Or, the tray may be filled with sheets in single order, starting with the first sheet 70 and with sets of carbon and copy sheets in alternation until the proper number of units have been built up. The object of the tray 75 14 is not only to serve as a rest for the assembly of sheets, but to aline them as they are grouped without extra effort and place them closer to the operator. With the grouping done, the operator simply pushes the tray back until it clears the typewriter platen 80 and bodily removes the batch of sheets for insertion behind the platen as before. It will be noted the incline of the tray 14 is materially less than that of the other shelves, in order that the tray may be placed at rest in any 85 position without its sliding forward by gravity.

The front end of the tray 14 is also cut out in the middle as indicated at 41a for a handy view of the front ends of the sheets to see that they are even; and such end also has an upbent lip 14b to limit these sheets. The sides of the tray are cut in, as indicated at 14c, near the front end for facility in lifting out the batch of sheets with the hands. It 90 is preferable that the tray be extended a short distance from the cabinet when the sheets are to be lifted out, and this position may be fixed by causing the tray to be made with a slot 14d engaging a tongue 5a projected upwardly from the bottom of the cabinet; and this tongue may also form a stop for the tray when it is fully inserted in the cabinet, to prevent the tray from sliding out. 95 100 105

It will be seen that the novel cabinet is an accessory which relieves the operator of time and energy consuming details in the task of assembling and training the paper sheets into the proper order and typewriter entrance; and the cabinet also serves as a storage container of ample capacity for routine needs; and finally, it is conducive to better speed, less confusion and greater efficiency on the part of the operator. For a better approach to the shelves with the hands, the shelves are built to progressively recede 110 from the front in an upward course. 115 120 125

I claim:—

1. In combination, a support adapted to be positioned behind a typewriter, the upper surface of said support being higher than any point on said typewriter, a cabinet on said support, said cabinet comprising a plurality of inclined shelves for storing paper and carbon sheets in the order in which the same are to be assembled prior to feeding into 130

said typewriter, said shelves having lips at the forward edges thereof to retain the paper thereon, and an inclined extensible assembling tray disposed below said shelves for receiving said sheets, the degree of inclination of said assembling tray being less than the degree of inclination of said shelves, said tray having slots at the sides thereof for facilitating the removal of assembled sheets.

10 2. In combination, a base adapted to be positioned behind a typewriter, the upper surface of said base being higher than any point on said typewriter, and a cabinet for paper supported on said base, said base having slideways whereby said cabinet may be adjusted toward and away from said typewriter.

In testimony whereof I affix my signature.
FRED W. NEELY.
